ADHESIVE APPLYING MECHANISM

Stewart J. White, Jersey City, N. J., Roswell H. Simpson, Staten Island, N. Y., and Edward Meola, Jersey City, N. J., assignors to Joseph Dixon Crucible Company, Jersey City, N. J., a corporation of New Jersey

Application February 3, 1943, Serial No. 474,552

11 Claims. (Cl. 91—47)

This invention relates to adhesive applying mechanism and particularly to mechanism for applying glue to the cap or ferrule of a pencil.

It has been customary for many years to use metal caps on pencils and to secure the caps to the pencils and the plugs or erasers in the caps by pricking the metal cap.

At the present time, due to the necessity of conserving metal, caps of paper, plastic or other non-metallic material are used. The cap is secured to the pencil and the plug is secured to the cap by adhesive or glue.

This invention has for its salient object to provide simple, practical and effective means for applying glue or adhesive to parts to be glued.

Further objects of the invention will appear from the following specification taken in connection with the drawings which form a part of this application, and in which

Fig. 1 is a vertical sectional elevation through a device or mechanism constructed in accordance with the invention, this view being taken substantially on line 1—1 of Fig. 4, looking in the direction of the arrows;

Fig. 2 is a sectional elevation taken substantially on line 2—2 of Fig. 5, looking in the direction of the arrows;

Fig. 3 is a sectional elevation taken substantially on line 3—3 of Fig. 1, looking in the direction of the arrows;

Fig. 4 is a sectional elevation taken substantially on line 4—4 of Fig. 5, looking in the direction of the arrows;

Fig. 5 is a sectional elevation taken substantially on line 5—5 of Fig. 4, looking in the direction of the arrows; and

Fig. 6 is a sectional elevation taken substantially on line 6—6 of Fig. 5, looking in the direction of the arrows.

The invention briefly described consists of adhesive applying mechanism comprising a container for the adhesive, an apertured member movable through the adhesive, and reciprocatable means which is also preferably rotatable for discharging the adhesive from the apertures and transferring the adhesive to the parts to be glued.

Further details of the invention will appear from the following description.

In the particular embodiment of the invention illustrated in the drawings, the mechanism comprises a main frame member or casing 10 having a cover 11 at one side thereof and a cover 12 at the other side thereof, the latter cover including a cover plate 13.

The main casing 10 is carried by a bracket 15

and is adjustably mounted thereon in the following manner. An L shaped support or bracket 16 is adjustably secured to the end of the bracket 15 by a bolt 17 which extends through a slot 18 in one arm of the L shaped member 16. A stud 19 is threaded into the end of the bracket 15 and has a groove 20 which receives a flange or lug 21 formed on the upper end of the vertically extending arm of the L shaped bracket 16. The bracket 16 is vertically adjusted by the stud 19 and after it has been adjusted thereby it is clamped in place by the stud 17. Suitable guideways are provided between the outer end of the arm of the bracket 15 and the vertical arm of the L shaped bracket 16.

The casing 10 has a plate 25 secured to the upper surface thereof and the plate 25 has a longitudinal rib 26 which forms a horizontal guideway and extends into a correspondingly shaped groove 27 in the under surface of the horizontal portion 28 of the L shaped support or bracket 16. A stud 29 extends through the portion 28 which is slotted to receive the stud and is threaded into the plate 25.

The main casing 10 is provided with bearings 30 and 31 in which is rotatably and slidably mounted a spindle 32 having at one end thereof a portion 33 provided with a spiral groove 34. A collar or bushing 35 is secured to the outer end of the bearing 30 and is provided with a lug 36 which extends into the spiral groove 34. Thus, as the spindle 32 is moved longitudinally in the bearings 30 and 31 in a manner hereinafter described, the spindle will be simultaneously rotated on its axis.

The spindle 32 has secured to one end thereof a plunger 40, a flange 41 being provided at the end of the spindle and at the inner end of the plunger 40.

The spindle 32 is reciprocated by means of a yoke 45 having a bifurcated end 46 positioned in the groove of a collar 47 mounted on the spindle. The other end of the yoke 45 has an angular extension 48 which is secured to a plate 49 which is slidably mounted in guideways 50 formed in a plate 51 which is secured to one wall of the casing 10. This wall is provided with longitudinally extending slots 52 and 53. The yoke 45 extends through the slot 52, as shown in Figs. 4 and 6. From the showing in Fig. 4 it will be noted that the guideways between the plates 49 and 51 are beveled, and that the plate 49 engages the outside of the wall 55 of the casing 10.

The plate 49 has secured thereto an outwardly extending stud 60 which extends through a slot

61 in the cover plate 13 and has connected thereto an arm or link 62 by means of which the plate 49 is reciprocated.

As the plate is reciprocated in the manner just described, the spindle 32 will also be reciprocated and due to the spiral groove 34 and lug 38 the spindle will also be simultaneously rotated.

During this motion the plunger 40 will be moved into and through one of a plurality of apertures 65 formed in a disk 66 which is carried by a shaft 67 rotatably mounted in bearings 68 and 69 carried by the casing 10. The shaft 67 is intermittently rotated in the following manner. This shaft has mounted thereon a worm wheel 70 which is intermittently engaged by a tooth 71 carried by an arm 72 which extends through the slot 53 and has a right angle extension 73 which extends through a slot 74 formed in the plate 49. The outer end of the extension 73 has secured thereto a spindle 75 which is rotatably mounted in lugs 76 carried by the outside of the plate 49. A spring 77 surrounds the spindle 75 and normally holds the arm 72 and tooth 71 in position to engage one of the teeth of the worm wheel 70 when the tooth and arm are moved to the left, viewing Fig. 1. During the return movement of the plate 49 and the parts carried thereby, including the arm 72, the spring 77 permits the arm to raise so that the arm and tooth may return to their original position without causing the worm gear 70 and shaft 67 to rotate.

The disk 66 during its rotation passes through adhesive contained in a receptacle or container 80 which is detachably supporting by interengaging flanges 81 and 82 and a latch 83 on the bottom of the casing 10. Adhesive is supplied to the receptacle 80 from an inverted container 84 which is supported in a sleeve or cylindrical casing 85 having a downwardly extending portion 86 which is supported in an opening 87 in the casing 10.

In order to remove air from the apertures carried back into the receptacle 10 and to fill the apertures with adhesive, there is provided a plunger 88 which is carried by an arm 89 secured to the reciprocatable plate 49. As shown particularly in Fig. 6, the plunger 88 registers with each aperture as it reaches a predetermined position of rotation and is projected into the aperture, thereby removing air therefrom which has been carried around after the operation of the plunger 40 which discharges the adhesive from the apertures and transfers it to the article to be glued. As the plunger 88 is retracted through each opening 65, adhesive is drawn thereinto.

The invention above described was developed particularly for depositing adhesive or glue in the cap or ferrule of a pencil. Fig. 1 shows a pencil P supported in any suitable support 90 in a position in alignment with the axis of the spindle 32 and plunger 40. The disk 66 is rotated intermittently in the manner above described and when each aperture reaches a position opposite the pencil, the plunger 40 is operated in the manner shown in Fig. 1 and is projected into the cap or ferrule 95 which is positioned on the shouldered end 96 of the pencil P. As the plunger passes through the aperture 65, the glue in the aperture will be carried by the plunger into the open end of the ferrule or cap 95 and will be evenly distributed therein since the plunger rotates during its axial movement. Fur-

thermore, the rotation and reciprocation of the plunger into the cap will force adhesive into the inner end of the cap which is mounted on the shouldered end 96 of the pencil P. After the plunger 40 has performed its operation it is withdrawn and the disk then rotates to bring another aperture into alignment with the next pencil and the foregoing operation is repeated. During the passage of the apertures through the adhesive into the receptacle 80, the plunger 88 operates in the manner hereinbefore described to remove air from the apertures and to supply adhesive thereto.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What we claim is:

1. Adhesive applying mechanism comprising an adhesive container, apertured means movable through adhesive in said container, means for moving said means through the container with an intermittent movement, and means movable through the apertures in said apertured means to eject the adhesive therefrom and apply the adhesive to the article to receive said adhesive.

2. Adhesive applying mechanism comprising an adhesive container, apertured means movable through adhesive in said container, means for moving said means through the container with an intermittent movement, and reciprocable and rotatable means movable through the apertures in said apertured means to eject the adhesive therefrom and apply the adhesive to the article to receive said adhesive.

3. Adhesive applying mechanism comprising an adhesive container, apertured means movable through adhesive in said container, means for moving said means through the container with an intermittent movement, means movable through the apertures in said apertured means to eject the adhesive therefrom and apply the adhesive to the article to receive said adhesive, and means movable into and out of said apertures for removing air from the apertures and supplying adhesive thereto.

4. Adhesive applying mechanism comprising an adhesive container, apertured means movable through adhesive in said container, means for moving said means through the container with an intermittent movement, means movable through the apertures in said apertured means to eject the adhesive therefrom and apply the adhesive to the article to receive said adhesive, and means movable into and out of said apertures when the apertures are disposed in the adhesive in the container for removing air from the apertures and supplying adhesive thereto.

5. In combination, means for supporting a member to receive adhesive, a container for adhesive, a disk rotatably mounted above the container and having apertures movable into and out of said adhesive as the disk is rotated, means for rotating said disk in a step by step movement, said disk being movable thereby into positions in which the apertures are disposed opposite to and in alignment with said member, and means movable through said apertures for removing air from the apertures and supplying adhesive thereto.

6. In combination, means for supporting a

member to receive adhesive, a container for adhesive, a disk rotatably mounted above the container and having apertures movable into and out of said adhesive as the disk is rotated, means for rotating said disk in a step by step movement, said disk being movable thereby into positions in which the apertures are disposed opposite to and in alignment with said member, means movable through said apertures to carry the adhesive from the apertures to the member, and means movable through said apertures for removing air therefrom after said adhesive applying means has been actuated through the apertures.

7. In combination, means for supporting a tubular member to receive adhesive, an apertured adhesive carrying member, and reciprocable and rotatable means movable through the adhesive carrying member for transferring the adhesive from the carrying member to the tubular member.

8. In combination, means for supporting a tubular member to receive adhesive, an apertured adhesive carrying member, and reciprocable and rotatable means movable through the adhesive carrying member and into and out of said tubular member for transferring the adhesive from the carrying member to the tubular member.

9. Adhesive applying mechanism comprising an adhesive container, rotatable apertured means movable through adhesive in said container, means for moving said means through the container with an intermittent movement, and means movable through the apertures in said apertured means to eject the adhesive therefrom and apply the adhesive to the article to receive said adhesive.

10. In combination, means for supporting a tubular member to receive adhesive, an apertured adhesive carrying member, and reciprocable and rotatable means movable through the apertures in said member for transferring the adhesive from the carrying member to the tubular member.

11. In combination, means for supporting a tubular member to receive adhesive, an apertured adhesive carrying member, and reciprocable means movable through the apertures in said member for transferring the adhesive from the carrying member to the tubular member.
